UNITED STATES PATENT OFFICE.

THOMAS WIDDOP, OF BURNTFORK, WYOMING.

GLAZIER'S POINT.

SPECIFICATION forming part of Letters Patent No. 761,569, dated May 31, 1904.

Application filed June 3, 1903. Serial No. 159,945. (No model.)

To all whom it may concern:

Be it known that I, THOMAS WIDDOP, a citizen of the United States, residing at Burntfork, in the county of Sweetwater and State 5 of Wyoming, have invented new and useful Improvements in Glaziers' Points, of which the following is a specification.

My invention relates to new and useful improvements in glaziers' points; and its object 10 is to provide a point so constructed as to securely engage a window-sash and hold a light of glass in position therein without the use of putty.

One of the great objections to the points 15 ordinarily employed is that they fall from position within the sash when the putty becomes displaced, and the glass is therefore left without any means for retaining it in position.

My invention consists in providing a device 20 of this character having prongs extending therefrom, both of which are adapted to be placed into engagement with the sash, and thereby securely fasten the point in position against accidental displacement.

The invention also consists in the further 25 novel construction and combination of parts hereinafter more fully described and claimed, and illustrated in the accompanying drawings, showing the preferred form of my invention,

and in which—

Figure 1 is a perspective view showing one 30 of my improved glaziers' points attached to one of the sides of a window-sash. Fig. 2 is a similar view of a modified form of point attached to an intermediate cleat of a sash. Fig. 3 is a detail view of the point shown in Fig. 1. Fig. 4 is a view of a blank from which said point is formed. Fig. 5 is a detail view of a modified form of point shown 35 in Fig. 2, and Fig. 6 is a view of the blank from which it is formed.

Referring to the figures by numerals of reference, 1 is a plate having a prong 2 extending from the inner end thereof and in alinement therewith. Extending from this plate 40 at opposite sides of the prong 2 is a forked L-shaped extension 3, having a prong 4 at its free end, which extends downward therefrom

at an angle thereto. A glazier's point when constructed in this manner is preferably 50 formed of a blank such as shown in Fig. 4 and which comprises a substantially rectangular plate provided with a V-shaped extension. A V-shaped slot is formed within the plate, and the blank is adapted to be bent 55 upon the dotted lines shown in Fig. 4, so as to form the plate 1, forked plate 3, and prongs 2 and 4. After a light of glass has been placed within a window-frame the point herein described is placed with plate 1 thereon, and the 60 prong 2 is then inserted laterally into the window-sash 5. Prong 4 is then forced downward into sash 5 at right angles to the prong 2, and it is obvious that the plate 1 will thus be held firmly in position upon the glass. 65 Putty can, if desired, be placed over the plate 1 after it has been fastened in position.

A modified form of glazier's point is used upon the intermediate cleats of a window-sash, and this modification has been illustrated in Figs. 2, 5, and 6. It comprises a substantially U-shaped plate 6, the ends of which are forked, as shown at 7, and extending in opposite directions from these forked ends are V-shaped extensions 8, having integral prongs 9 at their inner ends in alinement with the openings formed within the forked ends of plate 6. To secure this modified form of point in position, the U-shaped plate 6 is placed over the cleat 10, and the prongs 9 are 80 then pressed inward, so as to engage the opposite sides of the cleat. The extensions 8 will thus retain the glass in position upon the sash and prevent displacement thereof. As shown in Fig. 6, this modified form of point 85 is preferably formed of a rectangular plate having V-shaped extensions at the ends thereof, and V-shaped slots are cut in the plate, so that when the same is bent upon the dotted lines shown in Fig. 6 the parts will assume 90 the positions shown in Fig. 5.

In the foregoing description I have shown the preferred form of my invention; but I do not limit myself thereto, as I am aware that modifications may be made therein without 95 departing from the spirit or sacrificing any of

the advantages thereof, and I therefore reserve the right to make such changes as fairly fall within the scope of my invention.

Having thus described the invention, what is claimed as new is—

1. A glazier's point comprising a plate, an angular-shaped extension on one edge thereof, and a prong struck from said extension and in alinement with the plate, said prong and a portion of the extension being in parallel planes.
2. A glazier's point comprising oppositely-

arranged similar plates, an angular extension intermediate and integral with the plates, and inwardly-extending prongs struck from said extension and arranged in alinement with each other and with the plates, said prongs being parallel with a portion of the extension. 15

In testimony whereof I affix my signature in presence of two witnesses.

THOMAS WIDDOP.
